(57) **CLAIM**

The ornamental design for a knit hat with bow, as shown and described.

DESCRIPTION

FIG. 1 is a front right top perspective view of the knit hat with bow, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The evenly-sized broken lines shown in FIG. 7 define the bounds of the claimed design and form no part of the claimed design.

1 Claim, 7 Drawing Sheets
